[57] CLAIM

The ornamental design for a front bezel for a consumer electronic appliance, as shown and described.

DESCRIPTION

FIG. 1 is a front, top and right side perspective view of the front bezel showing our new design mounted on a set-top television terminal shown in phantom;

FIG. 2 is a top plan view of the bezel;

FIG. 3 is a front elevational view of the bezel;

FIG. 4 is a left side elevational view of the bezel;

FIG. 5 is a right side elevational view of the bezel; and,

FIG. 6 is a bottom plan view of the bezel.

The rear is plain and unornamented. The broken line showing of an electronic appliance is for illustrative purpose only and forms no part of the claim.
